PUSHBUTTON ELECTRIC SWITCH

Charles C. Davis, Aurora, Ill., and Raymond L. Erickson, Brookfield, Wis., assignors to Cutler-Hammer, Inc., Milwaukee, Wis., a corporation of Delaware

Continuation of design applications Ser. No. 86,536 and Ser. No. 86,541, Aug. 11, 1965. This application Aug. 1, 1966, Ser. No. 3,899

Term of patent 14 years

(Cl. D26—13)

Fig. 1

Fig. 2

Fig. 3

Fig. 4

Fig. 5

Fig. 6

Fig. 7

FIGURE 1 is a front perspective view of a pushbutton electrical switch showing our new design;

FIG. 2 is a side elevational view thereof, partially in section;

FIG. 3 is a bottom plan view thereof, partially in section;

FIG. 4 is a front perspective view of the switch of FIG. 1 showing a modified embodiment thereof, wherein a third rectangular pushbutton is provided at one side of the two larger buttons;

FIG. 5 is a side elevational view thereof, partially in section;

FIG. 6 is a view similar to FIG. 4 but showing one of the pushbuttons depressed; and

FIG. 7 is a bottom plan view thereof partially in section.

The essential features of our design are shown in full lines.

This application is a continuation of our copending applications, Ser. Nos. D. 86,536 and D. 86,541, each filed Aug. 11, 1965, and now abandoned.

We claim:

The ornamental design for a pushbutton electric switch, as shown and described.
